RAILWAY TRACK CIRCUIT APPARATUS

Paul P. Sosinski, Edgewood, Pa., assignor to The Union Switch & Signal Company, Swissvale, Pa., a corporation of Pennsylvania

Application August 15, 1934, Serial No. 739,946

21 Claims. (Cl. 246—41)

My invention relates to railway signaling apparatus of the type involving track circuits, and has for an object the provision, in apparatus of this type, of a novel and improved track circuit including a relay which will respond to the decrease in current supplied to it when the train enters the associated section, but which will not respond to track circuit current of steady value or to gradual changes in the current supplied to the relay due for example to changes in ballast conditions.

I will describe two forms of apparatus embodying my invention, and will then point out the novel features thereof in claims.

In the accompanying drawing, Fig. 1 is a diagrammatic view showing one form of apparatus embodying my invention. Fig. 2 is a view showing a modification of a portion of the apparatus shown in Fig. 1, and also embodying my invention.

Similar reference characters refer to similar parts in each of the views.

Referring first to Fig. 1, the reference characters 1 and 1^a designate the track rails of a stretch of railway track along which traffic normally moves in the direction indicated by the arrow. These rails are divided by insulated joints 2 to form a plurality of track sections, of which only one complete section, D—E, is shown in the drawing. Traffic moving through section

D—E from left to right is governed by a signal K, which, as here shown, is a light signal comprising a proceed lamp G, a caution lamp Y, and a stop lamp R.

Section D—E is provided with a track circuit comprising a battery H connected across the rails at the exit end of the section and a neutral relay P, a transformer T and a neutral relay A, all receiving energy from the rails at the entering end of the section. Relay P has a holding circuit which passes from rail 1, through the primary 3 of the transformer T, a portion 6 of the operating winding of the relay P, a resistance 7, a front contact 8 of the relay P, and a back contact 5 of the relay A to rail 1^a. Relay P also

has a pickup circuit which passes from rail 1 through the primary 3 of the transformer T, the entire operating winding of the relay P, and a back contact 11 of a relay S to rail 1^a. The secondary 4 of the transformer T is connected, in series with a rectifier Q, to the operating winding of the relay A.

Relay S is a neutral relay controlled by a front contact 9 of the relay P and energized by a battery 10.

Associated with relays A, P and S is a fourth

relay F, which is a distant relay controlled by the following circuit: From terminal B of a suitable source of current at location E, through front contact 13 of relay S¹ at location E, and winding of relay F, to terminal C of the same source of current. 5

The proceed lamp G is provided with a circuit which passes from terminal B, through front contact 12 of relay S, front contact 14 of relay F, and lamp G to terminal C of the same source 10 of current. The caution lamp Y is provided with a circuit which passes from terminal B, through front point of contact 12 of relay S, back point of contact 14 of relay F, and lamp Y to terminal C. The stop lamp R is provided with a 15 circuit which passes from terminal B, through back point of contact 12 of relay S, and lamp R to terminal C.

The operation of the system is as follows: When section D—E is unoccupied, relay A is de- 20 energized, relay P is energized by current from battery H, and relay S is energized by current from battery 10. If the section next in advance is also unoccupied, relay F is energized. Lamp G will then be lighted so that the signal will indicate proceed. If, however, the section in advance of point E is occupied by a train, relay F will be deenergized, so that lamp Y will be lighted and signal K will indicate caution. 25

I will now assume that a train enters section 30 D—E. When this occurs, the shunt afforded by the wheels and axles of such train will suddenly reduce the amount of current flowing in primary 3 of transformer T, and this sudden change in the primary current will induce an impulse of 35 current in secondary 4 of such polarity as to momentarily energize relay A, opening back contact 5. The momentary opening of back contact 5 will open the holding circuit for relay P which in turn will release relay S. The deenergization of relay S will open the circuit for the proceed lamp G or the caution lamp Y at front point of 40 contact 12 of relay S and will close the circuit for stop lamp R at back point of contact 12. Signal K will then indicate stop. Relay P will remain down due to the train shunt so long as 45 section D—E is occupied by a train.

When the train leaves section D—E, there will be a sudden increase in the amount of current supplied to primary 3 of transformer T and this 50 sudden change in the primary current will cause an impulse to be induced in secondary 4 of a polarity opposite to that generated when the train entered the section. Rectifier Q will prevent the flow of this current of opposite polarity 55

through the winding of relay A and relay A will not be energized. Relay P will be energized by the pickup circuit which includes the full winding 6 and back contact 11 of relay S. The energization of relay P will energize relay S through front contact 9 of relay P. The energization of relay S will open the pickup circuit and restore the holding circuit for relay P. Relay F will have become deenergized due to the train entering the section in advance of section D—E, and so signal K will indicate caution until the train passes out of such section in advance, when it will again indicate proceed.

Rectifier Q is not essential, however, because a 16 momentary pickup of relay A, when the train leaves the section D—E, is of no consequence, since back contact 5 of relay A has ample time to reclose and thus establish the holding circuit for relay P through front contact 8 of relay P, before 20 the pickup circuit for relay P is opened by back contact 11 of relay S.

The operation of relay A is independent of the track energy level at the left-hand end of section D—E, and is dependent only on the change 25 in the amount of current supplied to transformer T when a train enters the section. It follows that changes in the characteristics of the track circuit due to variations in weather or other conditions will not affect the operation of this relay. 30 Relay A is sufficiently sensitive to respond to a small change in the track circuit current such as would occur when the track is shunted during wet ballast conditions, therefore, a relatively poor shunt would actuate relay A during dry ballast 35 conditions because of the relatively large change in the track circuit current. Relay P, however, if relay A were not used, would require a relatively good shunt for releasing under dry ballast conditions. The combination of the two relays 40 A and P provides, therefore, for reliable shunting under all possible conditions of the track.

Referring now to Fig. 2, the apparatus shown in this view is the same as that shown in Fig. 1, except that relay A receives energy from a secondary winding 4^a of relay P wound in inductive 45 relation to the operating winding of relay P. With this arrangement, the maximum energization of relay P, which would ordinarily obtain under dry ballast conditions, must not be great 50 enough to saturate the relay core as, otherwise, the train shunt may not produce a sufficient change in the flux to operate relay A. The apparatus shown in Fig. 2 is otherwise the same as that shown in Fig. 1.

Although I have herein shown and described only two forms of apparatus embodying my invention, it is understood that various changes and modifications may be made therein within the scope of the appended claims without departing 60 from the spirit and scope of my invention.

Having thus described my invention, what I claim is:

1. In combination, a section of railway track, a source of current connected across the rails of 65 said section, a relay receiving energy from the rails of said section and responsive to the steady value of current with which it is supplied, and means also receiving energy from the rails of said section and responsive to the change in value 70 of the current received thereby due to the entrance of a train into said section but not responsive to the steady value of such current for momentarily disconnecting said relay from at least one rail of said section.

2. In combination, a section of railway track,

a source of current connected across the rails of said section, a relay receiving energy from the rails of said section and responsive to the steady value of the current with which it is supplied, and a second relay also receiving energy from the rails of said section and responsive to the change in the value of the current received thereby due to the entrance of a train into said section but not responsive to the steady value of such current, said second relay having an armature actuating a contact for momentarily disconnecting said first relay from one rail of said section. 5 10

3. In combination, a section of railway track, a source of current connected across the rails at one end of said section, a first relay receiving energy from the rails at the other end of said section and responsive to the steady value of current with which it is supplied, a second relay, means also receiving energy from the rails at 15 said other end of the section for energizing said second relay when the value of the current received by said means is changed due to the entrance of a train into said section, said means being incapable of responding to the steady value 20 of such current, and means controlled by said second relay for decreasing the energization of said first relay below the release point thereof. 25

4. In combination, a section of railway track, a source of current connected across the rails of said section, a primary relay, a secondary relay, a holding circuit for said primary relay connected across the rails of said section and including only a portion of the operating winding of the primary relay and a resistance, a pickup 30 circuit for said primary relay also connected across the rails of said section and including the entire operating winding of said primary relay and a back contact of said secondary relay, a circuit for said secondary relay including a front 35 contact of said primary relay and a source of current, and means also receiving energy from the rails of said section and responsive to the change in the value of the current received thereby due to the entrance of a train into said section for 40 momentarily opening said holding circuit for 45 said primary relay.

5. In combination, a section of railway track, a source of current connected across the rails of said section, a primary relay, a secondary relay, a holding circuit for said primary relay connected across the rails of said section and including only a portion of the operating winding of the primary relay and a resistance, a pickup 50 circuit for said primary relay also connected across the rails of said section and including the entire operating winding of said primary relay and a back contact of said secondary relay, a circuit for said secondary relay including a front 55 contact of said primary relay and a source of current, and a third relay also receiving energy from the rails of said section and responsive to the change in the value of the current received thereby due to the entrance of a train into said section and having an armature actuating a contact for momentarily disconnecting said primary 60 relay from one rail of said section. 65

6. In combination, a section of railway track, a source of current connected across the rails of said section, a primary relay, a secondary relay, a holding circuit for said primary relay connected across the rails of said section and including only a portion of the operating winding of the primary relay and a resistance, a pickup 70 circuit for said primary relay also connected 75

across the rails of said section and including the entire operating winding of said primary relay and a back contact of said secondary relay, a circuit for said secondary relay including a front 5 contact of said primary relay and a source of current, a third relay, means also receiving energy from the rails of said section for energizing said third relay when the value of the current received by said means is changed due to 10 the entrance of a train into said section, and means controlled by said third relay for decreasing the energization of said primary relay below the release point thereof.

7. In combination, a section of railway track, 15 a source of current connected across the rails of said section, a primary relay having a holding circuit receiving energy from the rails of said section and including a front contact of the primary relay, a secondary relay controlled by a front 20 contact of said primary relay, a pickup circuit for said primary relay receiving energy from the rails of said section and including a back contact of said secondary relay, and means also receiving energy from the rails of said section and 25 responsive to the change in the value of the current received thereby due to the entrance of a train into said section for momentarily opening said holding circuit for said primary relay.

8. In combination, a section of railway track, 30 a source of current connected across the rails of said section, a primary relay having a holding circuit receiving energy from the rails of said section and including a front contact of the primary relay, a secondary relay controlled by a front 35 contact of said primary relay, a pickup circuit for said primary relay receiving energy from the rails of said section and including a back contact of said secondary relay, and a third relay also receiving energy from the rails of said section 40 through a secondary winding of said primary relay and responsive to the change in the value of the current received thereby due to the entrance of a train in said section, said third relay having an armature actuating a contact for momentarily 45 disconnecting said primary relay from one rail of said section.

9. In combination, a section of railway track, 50 a source of current connected across the rails of said section, a primary relay having a holding circuit receiving energy from the rails of said section and including a front contact of the primary relay, a secondary relay controlled by a front 55 contact of said primary relay, a pickup circuit for said primary relay receiving energy from the rails of said section and including a back contact of said secondary relay, said primary relay having a secondary winding in inductive relation to the operating winding, a third relay connected to said secondary winding and responsive 60 to the change in the value of the current received thereby due to the entrance of a train in said section, said third relay having an armature actuating a contact for momentarily disconnecting said primary relay from one rail of said section.

10. In combination, a section of railway track, 65 a source of current connected across the rails of said section, a track relay receiving energy from the rails of said section and responsive to the steady value of current with which it is supplied, 70 a transformer also receiving energy from the rails of said section, and means including a normally deenergized auxiliary relay which becomes momentarily energized from said transformer in response to a change in the energization of the 75 transformer occurring upon the entrance of a

train into said section for decreasing the energization of said track relay below the release point thereof.

11. In combination, a section of railway track, 5 a source of current connected across the rails of said section, a main relay receiving energy from the rails of said section and responsive to the steady value of current with which it is supplied, a transformer having a primary which receives energy from the rails of said section, a normally deenergized auxiliary relay receiving energy momentarily from the secondary of said transformer in response to a change in the energy received by said primary occurring upon the entrance of a train into said section, and means 10 controlled by said auxiliary relay for decreasing the energization of said main relay below the release point thereof.

12. In combination, a section of railway track, 20 a source of current connected across the rails of said section, a first relay receiving energy from the rails of said section and responsive to the steady value of current with which it is supplied, a rectifier, a second relay having an operating circuit which includes said rectifier, 25 means also receiving energy from the rails of said section for energizing said operating circuit when the value of the current received by said means is changed due to the entrance of a train into said section, said means being incapable of energizing said operating circuit in response to a steady value of such current, and means controlled by said second relay for decreasing the energization of said first relay below the release 30 point thereof.

13. In combination with a section of railway track and a source of current connected across the rails of said section, a relay having an operating winding receiving current from the rails of said section and having a second winding in inductive relation with said operating winding, an auxiliary relay controlled by the current induced in said second winding when said section becomes occupied by a train, and means governed by said auxiliary relay for controlling the supply of current to said operating winding.

14. A track circuit for railroads comprising, in combination, a section of railway track, a source of unidirectional current connected across the track rails at one end of said section, a track 50 relay receiving energy from the track rails at the other end of said section, a transformer having its primary winding included in said track circuit at said other end of the section, and an auxiliary relay also at said other end of the section energized only by current induced in the secondary winding of said transformer, and operated in response to the relatively quick change of current in the track circuit caused by the entrance of a train into said section for decreasing 55 the current through said track relay to release its armature.

15. A track circuit for railroads comprising, in combination, a unidirectional source of current at one end of the track circuit and a track relay 65 in series with said source at the other end of the track circuit, a transformer having its primary winding included in said track circuit at said other end, and an auxiliary relay also at said other end of the track circuit energized only by 70 current induced in the secondary winding of said transformer and causing operation of a contact to a particular position only when current in one direction is induced in said secondary winding by the relatively quick change in the current in 75

said track circuit caused by the entrance of a train upon said track circuit, said contact when operated to said particular position acting to decrease the current through said track relay to 5 release its armature.

16. In combination, a section of railway track, a source of current connected across the rails of said section, a first relay receiving energy from the rails of said section and responsive to the 10 steady value of current with which it is supplied, a normally deenergized second relay, means for momentarily energizing said second relay due to the relatively high rate of change of current flow in said first relay when the current through 15 said first relay is quickly decreased upon the entrance of a train into said section, and means controlled by said second relay when energized for decreasing the energization of said first relay below the release point thereof.

20 17. In combination, a section of railway track, a source of energy supplying current to the rails of said section, a relay receiving current from the rails of said section, and means responsive to the rate of change of current flow in said relay 25 for completely disconnecting current from said relay when the current through the relay is rapidly decreased due to the entrance of a train into said section.

18. In combination, a section of railway track, 30 a source of energy supplying current to the rails of said section, a relay receiving current from the rails of said section, a transformer having its primary also receiving current from the rails of said section, and means governed by the 35 secondary of said transformer for completely disconnecting current from said relay upon a decrease in the current flowing in said primary due to the entrance of a train into said section.

19. In a track circuit for railroads, the combination with a section of railway track having 40 a track relay connected thereto at one end of the section and a source of unidirectional cur-

rent connected thereto at the other end of the section, a normally deenergized auxiliary relay separate from said track relay and located at said one end of the section, said auxiliary relay being effective when operated to decrease the 5 current through said track relay and thereby cause a release of its armature, and means including a transformer also at said one end of the section for causing a momentary operation of said auxiliary relay in response to the relatively quick change in the current in said track circuit caused by the entrance of a train into 10 said section.

20. A track circuit for railroads comprising in combination, a track relay at one end of the 15 track circuit, a source of unidirectional current at the other end of the track circuit for energizing said track relay, an inductive device at said one end of the track circuit, and a normally deenergized auxiliary relay also at said one end 20 of the track circuit receiving operating energy from the track circuit through said inductive device in response to the relatively high rate of change in the current in said track circuit produced by the entrance of a train upon said track 25 circuit for decreasing the current through said track relay and thereby causing a release of its armature.

21. In combination, a section of railroad track, a signal governing traffic over said section, a 30 source of energy connected across the rails at one end of said section, a track relay connected across the rails at the other end of said section and responsive to the current flow therein, electro-magnetic means responsive only to variations 35 in current flow in said track circuit to assume a particular magnetized condition of only one polarity during such variations, and means jointly controlled by said track relay and said electro-magnetic means for governing said signal. 40
